SAFETY PIN

Dante V. Bagnasco, Brooklyn, N. Y.

Application March 14, 1947, Serial No. 734,589

3 Claims. (Cl. 24—161)

1

This invention relates to a pin of the safety pin type which may be used either for utilitarian purposes or as an ornament.

It is an object of this invention to provide a pin which, when in use, will lie flat against the body so as completely to conceal the pin, and which will not make an unsightly lump in the surface of the outer garments, and which will not be uncomfortable to the wearer even if he should sit upon it. It is a further object to provide a pin which may be readily opened, but which, when in the closed position, will remain closed against accidental opening.

It is a further object to provide a pin in which the pin portion will be completely concealed within the body portion so that the body portion may be used as an ornament. It is a further object to provide a pin which may be made of ornamental material such as plastic, and yet which will be inexpensive to manufacture and reliable and durable in use.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

Fig. 1 is a perspective view of a pin embodying this invention. Fig. 2 is an enlarged fragmentary perspective of the clasp portion of the pin. Fig. 3 is a section on the line 3—3 of Fig. 1 showing the relation of the parts during the closing of the pin. Fig. 4 is a similar view when the pin is completely closed. Fig. 5 is a longitudinal view fragmentary central section showing the form of the clasp element. Fig. 6 is a view similar to Fig. 2 showing a modification of the device. Fig. 7 is a view similar to Fig. 5 of the modified form. Fig. 8 is a longitudinal section through the device of Fig. 1. Fig. 9 is a section on the line 9—9 of Fig. 8.

In the drawings, the numeral 10 comprises an elongated dished body portion affording a channel trough 11 within which the pin portion may be concealed, which trough is bounded throughout its periphery by a ridge 12 which is made much heavier at both ends to carry the other portions of the device.

Mounted within this ridge at one end of the body is a shank portion 13 of a pin 14. This

2

shank portion is embedded within a recess in the ridge in such a manner as to permit the pin to be substantially concealed within the trough when in the closed position, but to spring outwardly to the position shown in Fig. 1 during attachment.

At the other end of the body, and also embedded within an enlarged portion of the ridge 12 is the shank portion 16 of the catch 17. This catch has a spring portion 18 extending toward the center of the pin 14. This spring portion is formed with an obstruction 19 shaped to receive the end portion of the pin when the latter is in closed position, and with laterally and downwardly extending flanges 20.

The shank of the catch member is embedded in the material of the ridge, but the ridge at this end of the pin is hollowed out to afford a chamber for the receipt of the spring portion of the catch as shown at 21 in Figs. 1, 2 and 5 and 21a in Fig. 6. The upper surface of this hollowed-out portion is cut away as at 22 at the center to accommodate the obstruction 19, and to permit the end of pin 14 to enter, but the portion of the upper surface adjacent to the obstruction bears against the upper face of the flanges 20 when in a position of rest. The springiness of the catch is sufficient to permit the spring member to be depressed sufficiently to pass the free end of the pin 14 between the side flanges 20 and the upper surface of the hollowed-out portion, as will be seen from Fig. 3, but yet to permit the spring portion to spring back into place after the pin is inserted as shown at Fig. 4.

The inner edges of flanges 20 are bent away, as shown at 20a, from the surface of the interior of recess 21 so that, in opening the pin, the point may be slipped between the flange and the body to bend the clip inwardly to release the pin.

The construction shown in Figs. 6 and 7 is similar to that previously described except that the shank 23 of the catch is reversely bent downwardly to provide a flat section 24 which may be embedded in the material of the body, and to leave a portion 25 free within the recess 21a in order to give a greater length of spring to the spring portion of the device, thus reducing the possibility of the catch becoming permanently bent.

In connection with this modification, there is also shown a slightly different form of the catch itself in that a side flange 26 is provided only upon one side of the spring member, while the reverse side is bent underneath the pin as shown at 27 in order more firmly to hold the pin when in

its closed position. For some purposes it is desirable to have this portion 27 bent back closely adjacent to the flange 26 as shown at 28, close enough to resiliently retain the end of the pin 14 within the orifice 29 formed by the obtrusion 30 in the spring member. With this embodiment it will be seen that, in closing the pin, the pin point must first be pressed downwardly to pass between the flange 26 and the body, and then must be positively bent upwardly to pass through the passageway 28. In this latter position it is held in place until forcibly dislodged.

Since certain changes may be made in the above construction and different embodiments of the invention could be made without departing from the scope thereof, it is intended that all matter contained in the above description or shown in the accompanying drawings shall be interpreted as illustrative and not in a limiting sense.

I claim:

1. A pin comprising a body, a pin element attached at one end to one end of said body, spring-urged away from said body, flanges on the other end of said body extending inwardly toward each other, defining with said body a recess for the free end of the pin element, said flanges being stiff to resist bending under the strains imposed upon the pin element in use, and said flanges defining between their inner edges a slot, and a spring clip fixed within said recess having a free end extending across said slot and having an outwardly curved boss fitting within said recess, said clip being spring-held against the edges of said slot, said clip having on one edge of said boss a spring arm curved away from the adjacent flange, whereby said spring arm may be depressed by said pin element, when in engagement therewith, sufficiently to permit the free end of said pin element to pass below said spring arm and into said boss and whereby said spring arm when within said recess may be inserted between said curved end and said flange to depress the spring sufficiently to permit release of the pin.

2. A pin comprising a body, a pin element attached at one end to one end of said body, spring-urged away from said body, flanges on the other end of said body extending inwardly toward each other from the end and sides, defining with said body a recess for the free end of the pin element, said flanges being stiff to resist bending under the strains imposed upon the pin element in use, and said flanges defining between their inner edges and a slot, a spring clip fixed within said recess, having an arm extending toward said other end of said body by which the clip is at-

tached to said body, said clip having an outwardly curved boss in alignment with, and said clip being spring-held against, the edges of said slot, said clip having on one edge of said boss a spring arm curved away from the adjacent flange, whereby said spring arm may be depressed by said pin element, when in engagement therewith, sufficiently to permit the free end of said pin element to pass below said spring arm and into said boss and whereby said spring arm when within said recess may be inserted between said curved end and said flange to depress the spring sufficiently to permit release of the pin.

3. A pin comprising a body, a pin element attached at one end to one end of said body, spring-urged away from said body, flanges on the other end of said body extending inwardly toward each other from the end and sides, defining with said body a recess for the free end of the pin element, said flanges being stiff to resist bending under the strains imposed upon the pin element in use, and said flanges defining between their inner edges and a slot, a spring clip fixed within said recess, having an arm extending toward said other end of said body by which the clip is attached to said body, said clip having an outwardly curved boss in alignment with said slot and having a flat surface on each side of said boss within the recess, spring-pressed outwardly against the inner faces of said flanges, the edge of said flat surface being curved away from the adjacent flange, whereby said spring arm may be depressed by said pin element, when in engagement therewith, sufficiently to permit the free end of said pin element to pass below said spring arm and into said boss and whereby said spring arm when within said recess may be inserted between said curved end and said flange to depress the spring sufficiently to permit release of the pin.
